Primary Examiner—Kay H. Chin*Attorney, Agent, or Firm*—C. Emmett Pugh; Pugh/Associates[57] **CLAIM**

The ornamental design for a boat mooring line attachment system for compensating for varying tides, as shown and described.

DESCRIPTION

FIG. 1 is a perspective view of a boat mooring line attachment system for compensating for varying tides showing my new design, the broken lines are for illustrative purposes only and form no part of the claimed design; FIG. 2 is a top plan view thereof, the bottom view being identical;

FIG. 3 is a front elevational view thereof, the rear elevational view being identical;

FIG. 4 is a side elevational view thereof, the opposite side view being identical;

FIG. 5 is a perspective view of a second embodiment of the boat mooring line attachment system for compensating for varying tides;

FIG. 6 is a top plan view of FIG. 5, the bottom plan view being identical;

FIG. 7 is a front elevational view of FIG. 5, the rear elevational view being identical; and,

FIG. 8 is a side elevational view of FIG. 5, the opposite side elevational view being identical.
